UNITED STATES PATENT OFFICE.

RALPH W. ARMSTRONG, OF NEW YORK, N. Y., ASSIGNOR TO THE SAFETY CAR HEATING & LIGHTING COMPANY, A CORPORATION OF NEW JERSEY.

REGULATING SYSTEM.

1,163,306.

Specification of Letters Patent.

Patented Dec. 7, 1915.

Application filed November 10, 1910. Serial No. 591,588.

To all whom it may concern:

Be it known that I, RALPH W. ARMSTRONG, a citizen of the United States, residing at New York, in the county of New York and State of New York, have invented certain new and useful Improvements in Regulating Systems, of which the following is a full, clear, and exact description, such as will enable others skilled in the art to which it appertains to make and use the same.

This invention relates to regulating apparatus.

One of the objects thereof is to provide simple and effective means for regulating a function of an electric current.

Another object is to provide sensitive and accurate voltage regulating apparatus of reliable and durable construction.

Other objects are to provide a device of simple construction whereby apparatus of the above general nature may be rendered more certain and effective.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is shown one of many possible embodiments of this invention, Figure 1 is a diagrammatic view of the regulating apparatus connected to control the voltage of a lamp circuit; and Fig. 2 is a detail view of the magnetic brake.

Similar reference characters refer to similar parts throughout the drawings and specification.

It may here be noted as conducive to an understanding of certain basic principles of this invention that in the class of voltage regulating apparatus in which a so-called pilot is employed, when there arises a slight abnormality of potential, although the effect of this may be multiplied in the regulating apparatus, there is not, generally speaking, a maximum change of current in the actuating magnet of the regulator. It is obvious that with a greater variation in the

potential to be regulated, there would be a greater change in the pilot controlled coil. 55 Accordingly, with a slight change to which the apparatus must be sensitive for accurate regulation, the regulator is operated at a relatively low speed and the action of the apparatus is accordingly defective. The 60 present invention eliminates the above and other disadvantages by treating the subject along a radically different line.

Referring to the drawings, 1 represents any suitable dynamo, preferably of the constant potential type. Leads 2 and 3, constituting the main circuit of the dynamo, supply current to lamps or other translation devices 4 connected in parallel between said leads. A secondary battery 5 is bridged 70 across the main circuit in a manner to be charged by the dynamo and to aid in supplying current to the lamps. With the apparatus and devices connected in the manner described, it is desirable to maintain a 75 substantially constant voltage at the lamps, and in order that this result may be effectively and simply attained, a suitable resistance device 6 is connected in the lead 3 of the main circuit in series with the lamps 80 and between the same and the storage battery. Suitable switches may be included in the circuit as at 7 and 8, whereby the lamps may be completely disconnected from the source of current or be connected to receive 85 current solely from the battery. The resistance device herein illustrated comprises a pair of metal plates 9 and 10, to which the lead 3 is connected, and disposed between said plates are a plurality of carbon 90 disks 11 in electrical contact with each other and with the metal plates. Another metal plate 12, spaced from the plate 9 by insulating means 13, is formed with a hole 14 at its center, through which the toggle member 15 passes, the hole being of sufficient diameter to permit oscillating movement. The outer end of the member 15 is threaded to receive the nut 16, which is formed to provide a ball and socket joint with the plate 100 12. The member 15 extends through alining openings in the carbon disks and the plate 10, the openings being large enough to permit oscillation of the member without contact with the edges thereof. A lever 17 105 constituting the other member of the tog-

gle is pivotally mounted in any suitable manner as at 18, and is provided at its opposite end with an armature 19 formed and adapted to coact with the pole piece 20 of 5 an electro-magnet, the coil of which is denoted by the numeral 21. Armature lever 17 is pivotally connected to the adjacent end of member 15 at a point 22 between the ends of said lever and is constantly urged to 10 swing in one direction about the pivot 18 by means of the adjustable tension spring 23. It will be seen that movement of the armature lever under the influence of the spring tension will cause a compression of 15 the carbon disks with a consequent decrease of resistance in the lamp circuit.

The spring 23 is so adjusted and the various parts so formed and proportioned that, with a predetermined current flowing 20 through the coil 21, the spring pull is accurately balanced, throughout the stroke of the arm 17, against the magnet pull and the force required to compress the carbon disks, so that the armature lever may be 25 placed in any position throughout its stroke and will remain there, thus maintaining the resistance at any attained value. In order, however, to render this action more certain, a magnetic brake is supplied, comprising a 30 piece of steel or iron rod 24 held movably against the side of the pole piece 20 by means of a suitable bracket or socket member 25. The member 24 is free to move longitudinally, and when the apparatus is 35 in service its hardened end is held against the face of the armature 19 by the magnetic pull, thus introducing a constant mechanical friction, which resists the movement of the lever 17, with the result that considerable 40 unbalancing of the spring pull and magnetic pull must occur before the lever 17 will be moved in either direction. The magnet coil 21 may be connected to any source of current having substantially constant potential, but in the present embodiment, it is 45 connected in a shunt across the lamp circuit so as to be influenced by the lamp potential. The circuit through the coil is from the main 3, by wires 26 and 27, through the 50 coil 21, wire 28, resistances 29 and 30 to wire 31, thence to the main 2. The amount of current flowing through the magnet is controlled by means of a solenoid 32 connected to one side of the lamp circuit by 55 wire 31 and to the other side thereof by the conductor 33, which comprises a resistance 34.

35 is a lever pivoted substantially at its center of mass, as at 36, and having one of 60 its arms pivotally connected, as at 37, to the movable core 38 of the solenoid 32. An adjustable spring 39 is secured to the lever so as to oppose the pull of the solenoid and, depending from the lever 35, is a contact 65 member 40 adapted when the lever is moved

in one direction by the solenoid, to engage a contact member 41, and when said lever is rocked in the other direction under the influence of the spring 39, to engage a second contact member 42. The contact member 40 70 has an electrical connection by means of wire 43 with wire 28, a portion of this connection being flexible, as at 44, to facilitate the movement of the contact member. From contact 41 a wire 45 leads to the magnet 75 circuit at a point between the two resistances 29 and 30. From the contact 42 a wire 46, including a resistance 47, is connected to the main 3 by means of connection 26.

Having described the arrangement of 80 parts and the electrical connections, the operation of the regulating apparatus is as follows: Assuming the lamp circuit to be traversed by a current at normal voltage, ordinarily the armature 17 will stand in the 85 position shown and the lever 35 will also occupy the position shown with the contact member 40 disposed between and out of contact with either 41 or 42. Now, if the voltage of the lamp circuit should rise sufficiently, the pull of the solenoid 32 of the 90 relay will increase and move the contact 40 until it engages contact 41. The circuit through coil 21 will then be as follows: from main 3 through wires 26, 27, coil 21, wires 28, 43, contacts 40 and 41, wire 45, resistance 30 and wire 31 to the main lead 2. With these connections the resistance 29 is shunted out of the magnet circuit, increasing 95 the current through said magnet and increasing the pull upon the armature 19, which will start to move down and introduce more resistance into the lamp circuit by opening the carbon pile, this action continuing until the voltage is again brought back to normal, when the spring 39 will overcome the pull of the solenoid 32 and cause the contact 40 to move into mid-position between contacts 41 and 42. Then, as 100 normal current will be flowing through the magnet 21 and the parts are properly proportioned to that end, the armature will remain in the position reached, holding the attained resistance value in the lamp circuit. It will be noted that the solenoid 32 105 does not act until the voltage has reached a certain value, and then after the contact is made between members 40 and 41 the current flowing through the magnet coil 21 will be greatly augmented. Until this point is reached and this effect produced there will be no movement of the armature 19 for the slight increase in current due to the increase in voltage of the lamp circuit is not sufficient to overcome the balance of the parts, which is rendered more stable by the retarding action of the magnetic brake. If 110 the voltage of the lamp circuit should fall, the pull of the solenoid 32 of the relay will decrease, permitting spring 39 to move con- 115

tact 40 into engagement with contact 42. The circuit through the magnet coil 21 will then be as follows: the main 3, wires 26 and 27, coil 21, wire 28 to the point 48 and also 5 through wire 46, resistance 47, contact 42, contact 40, and wire 43 to the point 48, whence the current flows as before through resistances 29 and 30 and wire 31 to the main lead 2. It will be seen that resistance 10 47 is connected in shunt with coil 21 and the two in series with resistances 29 and 30 across the lamp circuit. The current through coil 21 will decrease and the armature 19 will move up under the action of the spring 23 15 to decrease the resistance in the lamp circuit by compressing the carbon pile, until the voltage shall return to normal, when the contact 40 will again move into mid-position between contacts 41 and 42 and the resistance of the carbon pile will again be held at the value attained.

It will accordingly be seen that in following out this invention cheap, simple and durable apparatus may be constructed which 25 will attain, among others, all of the ends and objects hereinbefore set forth and which in operation will be characterized by certainty of action combined with accuracy and sensitiveness.

30 As many changes could be made in the above construction and many apparently widely different embodiments of this invention could be made without departing from the scope thereof, it is intended that all 35 matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent is:

1. In regulating apparatus, in combination, a variable resistance, electrically controlled means adapted with a given current to maintain said resistance at any attained value, a plurality of circuits, each including said means, and electrically controlled 50 means adapted selectively to render effective said circuits, the circuit selected depending upon the value of the function to be regulated.

2. In potential regulating apparatus, in combination, a variable resistance, electrically controlled means adapted with a given current to maintain said resistance at any attained value, a plurality of circuits, each including said means, and potential controlled 55 means adapted selectively to render effective said circuits, the circuit selected depending upon the potential to be regulated.

effective said circuits, the circuit selected depending upon the potential to be regulated.

3. In potential regulating apparatus, in combination, a pressure controlled variable resistance, means comprising an electro-magnet adapted to hold said resistance at any stage of compression with a given current through said magnet, a plurality of circuits each including said magnet, and potential controlled means adapted selectively to render effective said circuits, the circuit selected depending upon the potential to be regulated.

4. In potential regulating apparatus, in combination, a pressure controlled variable resistance medium, means comprising a toggle adapted to vary the pressure upon said medium, means comprising an electro-magnet adapted to coact with said first means in holding said medium at any stage of compression with a given current through said magnet, a plurality of circuits each including said magnet, and potential controlled means adapted selectively to render effective said circuits, the circuit selected depending upon the potential to be regulated.

5. In potential regulating apparatus, in combination, a pressure controlled variable resistance medium, means comprising a toggle adapted to vary the compression of said medium, a spring tending to urge said toggle in one direction, an electro-magnet tending to urge said toggle in the other direction, said parts being formed and proportioned to hold said resistance at any stage of compression with a certain predetermined current flowing through said magnet, a plurality of circuits each including said magnet, and potential controlled means adapted selectively to render effective said circuits, the circuit selected depending upon the potential to be regulated.

6. In potential regulating apparatus, in combination, a pressure controlled variable resistance medium, means comprising a toggle adapted to vary the compression of said medium, means tending to urge said toggle in one direction, an electro-magnet tending to urge said toggle in the other direction, said parts being formed and proportioned to hold said resistance at any stage of compression with a certain predetermined current flowing through said magnet, a plurality of circuits each including said magnet, and potential controlled means adapted selectively to render effective said circuits, the circuit selected depending upon the potential to be regulated.

7. In potential regulating apparatus, in combination, a variable resistance, electrically controlled means comprising a regulating coil adapted with a given current to maintain said resistance at any attained value, a plurality of circuits having differ-

ent resistance values each including said coil, and potential controlled means adapted selectively to render effective said circuits, the circuit selected depending upon 5 the potential to be regulated.

8. In potential regulating apparatus, in combination, a variable resistance, electrically controlled means comprising a regulating coil adapted with a given current to 10 maintain said resistance at any attained value, a circuit leading through said coil, and potential controlled means adapted selectively with abnormal potential to shunt a portion of said circuit or to shunt a portion 15 of the current about said coil.

9. In potential regulating apparatus, in combination, a variable resistance, electrically controlled means comprising a regulating coil adapted with a given current to 20 maintain said resistance at any attained value, a circuit including artificial resistance and leading through said coil, and potential controlled means adapted selectively with abnormal potential to shunt a portion of 25 said artificial resistance or to shunt a portion of the current about said coil.

10. In potential regulating apparatus, in combination, a variable resistance, electrically controlled means comprising a regulating coil adapted with a given current to 30 maintain said resistance at any attained value, a circuit including artificial resistance, a second circuit forming a shunt about a portion of said resistance, a third circuit 35 including artificial resistance and forming a shunt about said coil, and potential controlled means adapted as the potential rises to close said second circuit and as the potential falls to close said third circuit.

40 11. In potential regulating apparatus, in combination, a variable resistance, electrically controlled means comprising a regulating coil adapted with a given current to maintain said resistance at any attained 45 value, a circuit leading through said coil, a contact member electrically connected to said circuit, a pair of contact members disposed on opposite sides of and normally out of engagement with said first contact member, 50 electrical connections between each of said pair of contact members and said circuit, a solenoid connected to measure the potential to be regulated and adapted with a rise of potential to move said first contact member 55 into engagement with one of said pair to shunt out a portion of said circuit and with a fall of potential to move the same into engagement with the other of said pair to shunt a portion of the current about said 60 coil.

12. In regulating apparatus, in combination, a pressure controlled variable resistance, means comprising an electro-magnet tending to hold said resistance at any stage 65 of compression with a given current through

said magnet, and a magnetic brake adapted to insure the proper action of said first means.

13. In regulating apparatus, in combination, a pressure controlled variable resist- 70 ance medium, a toggle adapted to vary the pressure upon said medium, an armature associated with said toggle, an electro-magnet adapted to coact with said armature in holding said medium at any stage of compression with a given current through said magnet, and a magnetic brake adapted to offer resistance to movement of said armature. 75

14. In regulating apparatus, in combination, a pressure controlled variable resist- 80 ance medium, means comprising a toggle adapted to vary the compression of said medium, a spring tending to urge said toggle in one direction, an electro-magnet tending to urge said toggle in the other direction, and a member adapted to be influenced by the magnetic pull to resist movement of said toggle in either direction, said parts being 85 formed and proportioned to hold said resist- 90 ance at any stage of compression with a certain predetermined current flowing through said magnet. 95

15. In potential regulating apparatus, in combination, a variable resistance, electrically controlled means adapted with a given current to maintain said resistance at any attained value, a magnetic brake for resisting the operation of said means, a plurality 100 of circuits, each including said electrically controlled means, and potential controlled means adapted selectively to render effective said circuits, the circuit selected depending upon the potential to be regulated. 105

16. In potential regulating apparatus, in combination, a pressure controlled variable resistance, means comprising an electro-magnet adapted to hold said resistance at any stage of compression with a given current through said magnet, a member adapted to coact with said magnet to aid in holding said compression, a plurality of circuits each including said magnet, and potential controlled means adapted selectively to render effective said circuits, the circuit selected depending upon the potential to be regulated. 110 115

17. In potential regulating apparatus, in combination, a pressure controlled variable resistance medium, means comprising a toggle adapted to vary the pressure upon said medium, means comprising an electro-magnet adapted to coact with said first means in holding said medium at any stage of compression with a given current through said magnet, a magnetic brake adapted to aid said parts in holding said compression, a plurality of circuits each including said magnet, and potential controlled means adapted selectively to render effective said 120 125 130

circuits, the circuit selected depending upon the potential to be regulated.

18. In potential regulating apparatus, in combination, a pressure controlled variable 5 resistance medium, means comprising a toggle adapted to vary the compression of said medium, a spring tending to urge said toggle in one direction, an electro-magnet tending to urge said toggle in the other direction, a member adapted to be influenced by the magnetic pull to resist movement of said toggle in either direction, said parts being formed and proportioned to hold said resistance at any stage of compression with 10 a certain predetermined current flowing through said magnet, a plurality of circuits each including said magnet, and potential controlled means adapted selectively to render effective said circuits, the circuit selected depending upon the potential to be regulated.

19. In potential regulating apparatus, in combination, a source of current, a current utilizing device bridged across the mains of 25 said source of current, a variable resistance device operatively related to said source of current to vary the voltage across said mains, an electro-magnet normally connected to be excited by a substantially constant 30 current, means adapted to coact with said magnet to maintain said resistance at any attained value with a given current through said magnet, and means shunted across said mains upon the current utilizing device side 35 of said variable resistance adapted to be electrically controlled selectively with abnormal potential to shunt a portion of said magnet circuit or to shunt about said magnet a portion of the current flowing in said 40 circuit.

20. In potential regulating apparatus, in combination, a source of current, a translation device bridged across the mains from 45 said source of current, a potential controlled variable resistance medium connected in series with said translation device, means comprising an electro-magnet adapted to hold said resistance at any stage of compression with a given current through said magnet, a 50 circuit including artificial resistance and leading through said magnet, and potential controlled means connected to measure the potential impressed upon said translation device and adapted selectively with abnormal 55 potential to shunt a portion of said artificial resistance or to shunt a portion of the current about said magnet.

21. In potential regulating apparatus, in combination, a source of current, a translation device bridged across the mains from 60 said source of current, a potential controlled variable resistance medium connected in series with said translation device, means comprising an electro-magnet adapted to hold 65 said resistance at any stage of compression

with a given current through said magnet, a member adapted to coact with said magnet to aid in holding said compression, a circuit including artificial resistance and leading through said magnet, and potential controlled means connected to measure the potential impressed upon said translation device and adapted selectively with abnormal potential to shunt a portion of said artificial resistance or to shunt a portion of the current about said magnet. 70

22. In potential regulating apparatus, in combination, a constant-potential source of current, a translation device connected and adapted to be supplied with current from 80 said source, a compressible pile resistance device connected in series with said translation device, means comprising a toggle adapted to compress said pile, an electro-magnet normally excited by a substantially 85 constant current, artificial resistance in the magnet circuit, a solenoid connected to measure the potential at said translation device, resistance means in a shunt about said magnet, and means controlled by said 90 solenoid and adapted with a rise in said potential to shunt out a portion of the resistance in said magnet circuit and with a fall in said potential to close said shunt about said magnet. 95

23. In potential regulating apparatus, in combination, a constant-potential source of current, a translation device connected and adapted to be supplied with current from 100 said source, a compressible pile resistance device connected in series with said translation device, means comprising a toggle adapted to compress said pile, resilient means tending to urge said toggle in one direction to compress said resistance, an electro-magnet adapted to urge said toggle in the other direction, a plurality of circuits alternatively connected to excite said magnet, and means controlled by the potential at 105 said translation device adapted selectively to render said circuits effective whereby the exciting current for said magnet is automatically varied in accordance with fluctuations in said potential. 110

24. In potential regulating apparatus, in combination, a constant-potential source of current, a translation device connected and adapted to be supplied with current from 115 said source, a compressible pile resistance device connected in series with said translation device, means comprising a toggle adapted to compress said pile, resilient means tending to urge said toggle in one direction to compress said resistance and an electro-magnet adapted to urge said toggle 120 in the other direction, a plurality of circuits adapted to be alternatively connected to excite said magnet, means controlled by the potential at said translation device adapted selectively to render said circuits 125 130

effective whereby the exciting current for said magnet is automatically varied in accordance with fluctuations of said potential, and a magnetic brake adapted constantly to 5 resist movement of said toggle.

25. In regulating apparatus, in combination, a pressure controlled variable resistance medium, a toggle adapted to vary the pressure upon said medium, an armature 10 associated with said toggle, and an electromagnet adapted to coact with said armature in holding said medium at any stage of compression with a given current through said magnet.

15. 26. In regulating apparatus, in combination, a pressure controlled variable resistance medium, means adapted to vary the pressure upon said medium, an armature associated with said means, and an electromagnet adapted to coact with said armature 20 in holding said medium at any stage of compression with a given current through said magnet.

27. In potential regulating apparatus, in 25 combination, a pressure controlled variable resistance medium, means comprising a toggle adapted to vary the compression of said medium, a spring tending to urge said toggle in one direction, and an electromagnet 30 tending to urge said toggle in the other direction, said parts being formed and proportioned to hold said resistance at any stage of compression with a certain predetermined current flowing through said magnet.

35. 28. In potential regulating apparatus, in combination, a pressure controlled variable resistance medium, means comprising a toggle adapted to vary the compression of said medium, means tending to urge said toggle in one direction, and an electromagnet tending 40 to urge said toggle in the other direction, said parts being formed and proportioned to hold said resistance at any stage of compression with a certain predetermined current flowing through said magnet.

45. 29. In regulating apparatus, in combination, a pressure controlled variable resistance medium, means adapted to cause varia-

tions of pressure upon said medium corresponding to the variations of mechanical resistance to compression offered by said medium, an armature associated with said means, and an electromagnet adapted to coact with said armature to hold said medium 50 at any stage of compression with a given current passing through said magnet.

30. In car lighting regulating apparatus, in combination, a pressure controlled variable resistance, and means to vary the pressure upon said resistance, including an armature and a voltage responsive electromagnet coöperable to hold said resistance at any one of a plurality of stages of compression 60 with a given current traversing said magnet.

31. In car lighting regulating apparatus, in combination, a pressure controlled variable resistance, and means to vary the pressure upon said resistance, comprising a voltage responsive electro-magnet, an armature therefor and a variable leverage connection between said armature and said resistance coöperable to hold the latter at any one of a plurality of stages of compression 70 with a given current traversing said magnet.

32. Regulating apparatus comprising, in combination, a pressure controlled variable resistance medium, a movable plate engaging one end of said medium, means including a toggle adjustably connected to said plate for varying the compression of said medium, a spring tending to urge said toggle in one direction, an armature associated with said toggle, and an electro-magnet 80 coöperating with said armature to urge said toggle in the other direction, said parts being formed and proportioned to hold said resistance at substantially any stage of compression with a given current traversing 85 said electro-magnet.

In testimony whereof I affix my signature, in the presence of two witnesses.

RALPH W. ARMSTRONG.
